MEANS FOR STRAIGHTENING KNITTING NEEDLES AND THE LIKE

Gustav Gastrich, Wyomissing, Pa., assignor to
Textile Machine Works, Wyomissing, Pa., a
corporation of Pennsylvania

Application May 29, 1935, Serial No. 24,012

16 Claims. (Cl. 266—2)

The present invention relates to a novel apparatus for treating knitting machine needles or similar articles and more especially concerns improvements in the method and apparatus for the handling of such articles during the heat treatment thereof, whereby to effect a straighter and more uniform finished product.

Knitting machine needles, such as the well known spring beard type, customarily are made from lengths of wire, each of which is fabricated to provide a shank with a short butt at one end and a grooved tapered portion at the other end, such latter end being rebent upon itself to form the integral spring beard of the needle. These articles on account of the very fine gauge of the wire necessarily require careful heat treatment to provide the proper ductility in the finished article. Ordinarily, after being formed, the needles are hardened, then drawn or tempered and, because of the warping which occurs in the needle as a result of molecular structural changes during such intermittent heating and cooling, finally straightened by hand. Most of the difficulties in the prior processes of treating needles occur at the time articles are taken in the red-heat state and quenched, which operation produces a distinct change in structure due to the variation in the cross section of the needles and to differences of temperatures at various points of the needles at the instant of quenching, the result being a variation in the internal and external stresses of any one needle and, therefore, more or less distortion of shape may occur.

From the hardening stage the needles are again heated in a liquid to remove the brittleness and to substantially release the aforesaid heterogeneous stresses. However, the needles having become crooked or irregular in hardening do not go back to their original straight form during the drawing operation. Once the original pre-formed needle is subjected to the inherent actions of the various heat treatment steps which tend to produce distortion therein, these needles never resume their original shape, even if such deleterious stresses are released by the drawing operation, and it has always been required prior to this invention to manually straighten knitting machine needles subsequent to their hardening and drawing.

This invention contemplates the provision of novel apparatus adapted to receive a plurality of knitting needles and to so engage such articles that they are firmly held in straight final form, and whereby the effect of structural changes incident to the drawing operation tends to perma-

nently retain the straightened condition of the needles and to overcome the natural tendency toward further distortion.

A further object of the invention is to provide a simple, efficacious device having means to substantially completely engage the entire outer surface of a plurality of knitting needles and at the same time to uniformly and accurately support the spring beards thereof throughout.

A still further object is to provide a novel spring-beard needle holding jig together with an element adapted to be inserted in the loop formed by the needle beard, whereby in such position to properly align a plurality of needles relative to the jig and at the same time to support the several components of the needle beards in opposition to the action of the clamp elements of the jig.

With these and other objects in view, which will become apparent from the following detailed description of the illustrative embodiments of the invention shown in the accompanying drawings, my invention resides in the novel elements of construction, devices and combination of parts in cooperative relationship, as hereinafter more particularly set forth in the claims.

In the drawings:

Figure 1 is a plan view of a preferred embodiment of the present invention;

Fig. 2 is a side elevation thereof; 30

Fig. 3 is a cross-section taken on the line 3—3,

Fig. 2;

Fig. 4 is a cross-section taken on the line 4—4,
Fig. 2;

Fig. 5 is a perspective view of the device with 35
the clamps removed and showing the slot structure thereof, and the association of several needles therewith together with the beard spacer bar;

Figs. 6 and 7 are front and side elevations, re- 40
spectively, of a spring beard needle illustrating certain irregularities in its contour as may occur during the heat treatment thereof;

Fig. 8 is a plan view of the device of Fig. 1 with the clamp plates removed and showing the 45
arrangement of knitting needles therewith;

Fig. 9 is a similar view showing the beard supporting plate in place;

Fig. 10 is a cross-section taken on the line 50
10—10, Fig. 8;

Fig. 11 is a cross-section taken on the line 55
11—11, Fig. 9;

Fig. 12 is a cross-sectional view on a much enlarged scale taken substantially on the line 56

12—12, Fig. 10, looking in the direction of the arrows;

Fig. 13 is a fragmentary perspective view of the beard spacing bar of the present invention illustrating the operative relationship thereof with the beard portion of a needle;

Figs. 14 and 15 are top and side elevational views partially in section, respectively, of a drawing tank adapted to receive the devices of this invention in spaced relationship;

Fig. 16 is a view similar to Fig. 15 illustrating a quenching tank; and

Figs. 17 and 18 are views similar to Figs. 6 and 7, illustrating the straightened condition of the finished needle, after being treated in accord with this invention.

The herein disclosed embodiment of my invention as illustrated in the accompanying drawings comprises a portable device so designed as to be capable of receiving a plurality of spring-beard knitting needles (generally two hundred or more) in spaced relationship and having integral and associated means adapted to engage the outer surfaces of the needles to render the contour of the same, in most instances, uniformly straight.

As has been mentioned above, knitting machine needles are made from a fine gauge steel wire and after forming, which changes their shape and cross sectional area at various points in their length, they must be hardened and then drawn to provide the proper ductility therein. Manifestly, when devices of such slender and varying contour are quenched from a red-heat there is produced a structure consisting of martensite, troostite, sorbite, etc., which distinctly differ in volumina. Wherefore, the differences in volumina and the irregular arrangement of the same produce heterogeneous stresses which cause a warping or distortion of the needle from its original straight form.

In the drawings, the novel device of Figs. 1 and 2 comprises a center base structure 20 having fixedly secured to one end a head piece 21, the latter forming with the base a substantially T-shaped cross-section. The base 20 may be of any suitable length depending upon the facility of handling and its accommodation to the drawing and baths or tanks. Each side 23 of member 20 is grooved or fluted from its rear edge 24 most of the way to the juncture of head piece 21 therewith, these parallel grooves 25 serving (see Fig. 5), as will presently be described, as means to receive and align a number of knitting needles.

Each of the grooves 25 is cut into the face of sides 23 to approximately the depth "D" of the knitting needles "N" (see Figs. 6, 7 and 17, 18) while the width of the grooves corresponds very closely to the width "W" of the needles, the latter dimension having just sufficient clearance to permit the manual insertion and removal of the needles in said grooves. The depth of grooves 25 is slightly less than the dimension "D", see Fig. 12, whereby to provide for the bottoming of the needles when the face plate clamps 26 are applied, as will be more fully described.

Adjacent the rear end of the grooves 25 each side 23 of the base 20 is milled to provide a relieved or stepped longitudinal groove 27, wherein are positioned the round ends 28 of the needle shanks adjacent the butts 29. The stems and the remainders of the shanks of the needles are flattened in manufacture and consequently width "W" thereof is somewhat narrower than the original wire gauge, which latter is retained in the

shank end portions 28 and butts 29. As will be seen in Figs. 5 and 10, the shoulder 31 between the flattened portion of the needle shank and the portion 28 lies contiguous to the inner edge of groove 27, and the grooves 25 extend substantially the full extent of the flattened sides of the needles.

In the process of making a spring beard needle there is pressed into the shank adjacent its upper end a longitudinally extending groove or eye 35 adapted to receive therein, in the manner usual to the function of a knitting machine, the pointed terminal end or tip of beard 36. The displacement of the material of the needle in the area of groove 35 causes a widening 37 of the needle at such point, and it is therefore, expedient to afford accommodation for the portion 37 in the inner or forward ends of needle recessed grooves 25. The spring beard needle to which the present embodiment of the invention is particularly directed is perfectly straight along its rear face 38 of the stem and flattened portion of the shank, which face, as will be apparent from the drawings, is bottomed in the grooves 25. Hence, the metal of the base member 20 may be further milled away as at 40 transversely across the needle grooves 25 in line with the start of the widened portion 37 of the needle stem when the latter is placed within the groove 25, thus providing clearance for portion 37 without sacrificing the supporting contact of the bottom of grooves 25 with the face 38 of the needle. As a matter of fact, the widened portions 37 of the needles are correspondingly less liable to stress distortion than that which occurs in the relatively narrower stem portion and by eliminating the side engagement of grooves 25 with only such widened portions of the needles no part of the advantages in the straightened functions of the present apparatus is lost.

The pointed upper end or head of the needle and the beard are slightly less in thickness than the width of the stem and it is desirable to provide a substantial support in the improved device for holding and straightening these fragile portions of the needles. In the drawings there is shown interposed between the base 20 and the T-head member 21 a plate 45 having its edges coextensive with the faces 23, 23 of the base member. This plate 45 has each of its edges provided with flutes or grooves 46 aligned with grooves 25 and which are dimensioned to snugly fit the narrowed upper ends of the needles.

Thus, as a needle is placed in a groove 25 it is supported on its rear side 38 upon the bottom of groove 25, the flattened portion 37 and the grooves 46, the sides of grooves 25 and 46 engaging the portions of the needles contiguous to portions 37. It is to be understood that the plate 45 inserted between base 20 and head 21 is provided only to facilitate the cutting of grooves 46, and that if desired such grooves may be formed directly in the base 20 and thus plate 45 be dispensed with.

Associated means are also provided to encompass the spring beard portion of a needle which, as is known, consists of a tapered portion rebent to overlie the groove 35 and a short angular pointed tip end 36. To facilitate the placement and removal of the needles in the present straightening device and means for engaging the respective angular and rebent portions of the beard are separate. Detachably secured to the head 21 by bolts or screws 50 are longitudinally extending plates 51 which overlie the faces 23 of base 20 and the

edge faces of plate 45. The inner edges, i. e., the portions 52 adjacent plate 45 of plates 51 are provided with flutes or grooves 53 aligned with grooves 25 and 46, and of a size corresponding to the thickness of the rebent portions of the beards of the needles. Thus, with this construction the upper end of a needle will be held by and between the facing grooves 53 and 46 of plates 51 and 45.

10 It is found desirable to also provide means fitting the looped space 54 formed by the needle beard in such manner as to firmly hold this part of the needle against distortion and at the same time to straighten any crookedness or irregularity 15 therein caused by the quenching of the article from the red-heat of hardening. At 55 is denoted a longitudinally extending beard spacer bar which (see Fig. 11) closely conforms to the facing surfaces of the beard loop 54. One edge 56 20 of the spacer bar 55 is rounded to fit the bend at the apex of the needle, the bottom and top are tapered to the exact shape of the corresponding surfaces of the needle head and beard portions and the other edge 57 is made of sufficient 25 height to insure the final correct spacing of the terminal point of the beard relatively to the needle groove 35. As seen in Fig. 9, the bars 55 extend from end to end of the device and each one serves to engage all of the needles on one 30 side 23 of the base 20.

In assembling needles in the grooves 25, they are placed therein by hand which of course results in only the substantial alignment of the needle beards. The spacer bar 55, described 35 above, is inserted into the beards of all the needles held on one side 23 of the jig, as by passing such bar from left to right of Figs. 8 and 9. To insure the unrestricted insertion of spacer bar 55 through the plurality of needle loops, one end 40 of such bar, see Fig. 13, is tapered both transversely and longitudinally to provide a blunt point 58. This point 58 will freely enter the beard loops, even though slightly out of alignment, and as the tapered or rounded portions 59 progress 45 through the loops the needles will be moved thereby to bring the apex bend of each needle in contact with edge 56 of the bar 55, thus bringing each needle in proper longitudinal alignment by forcing the appropriate portions into grooves 50 46 and 53.

From the foregoing it will be clear that when a needle is held by the receiving portions of the device described above such needle will be held substantially along its entire outer surface, and 55 it should be manifest that when a needle is engaged in grooves 25, 46 and 53, each being accurately formed, the same is given a straight and accurate final form.

It will also be understood that the transverse 60 width of faces 23 of base member 20 is intended to correspond to the height of the needles to be treated, i. e., the dimension from the bottom edge 24 adjacent the grooves 27 to the juncture of the head 21 approximates the length of the needle 65 from the bend at the beard to the butt portion thereof. Accordingly, when a needle is placed within a groove 25, the beard portion will project substantially to the inner end of such groove and of the grooves 46 and 53 while the butt end 70 29 will lie closely adjacent the rear edge of the base member 20. To further insure the accurate 75 positioning and alignment of the needles within the grooves 25, the plate 20 at its rear edge 24 adjacent the surface is provided with grooves 61 in right angular alignment with grooves 25.

These end grooves 61 as will best be seen in Figs. 4, 5 and 10, accurately engage with the butt portions 29 of the needles.

On each side of the base 20 and adapted to closely overlie the faces 23, 23 is the removable face plate clamp 26 having one side edge 60 terminating directly adjacent the lower rear edge of plate 51 so as to substantially cover the entire needle from butt to point. This edge 60 of clamp plate 26 is provided with a longitudinal groove 62 adapted to embrace the outermost rebent terminal portion of the needle beard as seen in the drawings. Suitable screws or bolts 63, 63 are employed to detachably secure the clamp plates 26 to the base 20.

Also, associated with the base member 20 is an end clamp device or plate 65 detachably secured by screws or bolts 66 to the rear side or end of base 20 as will best be seen in Figs. 3 and 4. This rear clamp plate 65 cooperates with the clamp 20 plates 26 to substantially enclose the entire outer surface of the needles held by the device.

The present novel needle straightening jig or device is very simple in operation and is adapted to receive and hold for straightening treatment 25 a considerable plurality of needles. To insert the needles in the jig the plates 26 and 65 are removed from the base, the spacer bar 55 being also removed, and the needles then are laid in the manner hereinbefore described in each of 30 the grooves 25. While in such position and before the clamp plates 26 are applied the spacer bars 55 are inserted from the end of the device through the needle beards, the butts 29 in end engagement in grooves 61 serving to properly 35 align such beard portion of the needles and to facilitate the insertion of these spacer bars 55. The clamp plates 26 and the plate 65 may then be screwed in place to firmly hold the needles in their respective grooves, the two side plates 26 40 providing a perfectly flat clamp surface 67 adapted to engage the edges 68 (Fig. 7) of the needles which become the front edges of the needles when in use. In the event (such as also shown in Fig. 7) the needles be distorted along 45 their vertical plane such clamp plates will force the needles into a straightened condition between the surface 67 thereof and the bottom of grooves 25. Any irregularity or lateral distortion in the shape of the needle stem or the flattened portion 50 of the shank is corrected by means of the surface contact in the grooves 25 and the pressure applied thereto by means of the clamp plates 26.

There is shown in Figs. 14 and 15 a conventional heat treating tank of the liquid type and having therein a removable basket 71 by which may be supported in the drawing medium 72 a plurality of the improved needle jigs of this invention, indicated in these figures of the drawings at 73. After the jigs 73 have been loaded in 55 accordance with the above description they are placed within a carrier basket 71 and immersed in the drawing fluid for the suitable time interval. They are then lifted from the tank 70 and quickly quenched in a cooling medium 74 within 60 the tank 75 as seen in Fig. 16 of the drawings.

It has been found by extensive tests and analyses that the present invention provides a very substantial saving in the cost of finishing knitting needles, principally in providing a method 70 by which the hand straightening of the knitting needles after heat treatment may be minimized. The present invention as described in the foregoing provides an improved method and apparatus adapted to receive a plurality of knitting 75

needles and to simultaneously straighten most of such needles at the time they are treated to draw the hardness therefrom which resulted from the red-hot hardening process.

5 It is to be understood that, while the above detailed description is more or less specific to the treatment of knitting machine needles, this invention has within its purview the adaptation of the novel method and apparatus for the similar 10 treatment of other knitting machine elements such as loop engaging points, transfer points, welt hooks, narrowing points and the like.

Accordingly, the improvements herein specifically shown and described, by which the desired 15 results are obtainable, can be modified and changed in various ways without departing from the spirit and scope of the invention as herein-after claimed.

I claim:

20 1. Apparatus for setting in straightened condition a spring-beard knitting needle and arranged to maintain the same in straightened condition during an annealing operation comprising a member having a groove therein complementary 25 in form to the rear and side surfaces of a finished needle, a groove at right angles adapted to receive the needle butt, said two grooves being coplanar, and cooperating clamp means adapted to force a needle into said grooves.

25 2. Apparatus for setting in straightened condition a spring-beard knitting needle and arranged to maintain the same in straightened condition during an annealing operation comprising a member having a groove therein complementary 30 in form to the rear and side surfaces of a finished needle, a groove at right angles adapted to receive the needle butt, said two grooves being coplanar, associated means adapted to engage with and support the needle beard in alignment 35 with said grooves, and a cooperating clamp member adapted to confine a needle within said grooves.

3. Apparatus for simultaneously setting in straightened condition, spring beard knitting 45 needles and arranged to maintain them in straightened condition during an annealing operation comprising a member having a plurality of parallel grooves therein, each groove being of a form complementary to the shape of the 50 stem of a finished needle, an end plate having beard receiving grooves therein coplanar with said first grooves, and a clamp plate adapted to cooperate with said member to confine needles within said grooves.

55 4. Apparatus for simultaneously setting in straightened condition, spring beard knitting needles and arranged to maintain them in straightened condition during an annealing operation comprising a member having a plurality 60 of parallel grooves therein, each groove being of a form complementary to the shape of the stem of a finished needle, said member having other grooves adapted to receive the angular 65 butt ends of said needles, an end plate having beard receiving grooves therein coplanar with the stem grooves in said member, and clamp means adapted to cooperate with said member to confine needles within said grooves.

5. Apparatus for simultaneously setting in 70 straightened condition, spring beard knitting needles and arranged to maintain them in straightened condition during an annealing operation comprising a base member having a plurality of parallel grooves on each side thereof, 75 each groove being of a form complementary to

the shape of the stem of a finished needle, said member also having coplanar right angular grooves adapted to receive the angular butt ends of said needles, and clamp plates adapted to cooperate with said member to confine needles within said grooves.

6. Apparatus for simultaneously setting in straightened condition, spring beard knitting needles and arranged to maintain them in straightened condition during an annealing operation 10 comprising a base member having a plurality of parallel grooves on each side thereof, each groove being of a form complementary to the shape of the stem of a finished needle, said member also having coplanar right angular 15 grooves adapted to receive the angular butt ends of said needles, an end plate covering one end of said grooves and having beard receiving grooves communicating with the grooves in said member, and clamp plates adapted to cooperate with the 20 grooved sides of said member to confine needles within said grooves.

7. Apparatus for simultaneously setting in straightened condition, spring beard knitting 25 needles and arranged to maintain them in straightened condition during an annealing operation comprising a base member having a plurality of parallel grooves on each side thereof, each groove being of a form complementary 30 to the shape of the stem of a finished needle, said member also having aligned right angular grooves adapted to receive the angular butt ends of said needles, an end plate covering one end of said grooves and having beard receiving grooves communicating with the grooves 35 in said member, a spacer element for confining the beards in associated grooves and for spacing said beards relative to the grooves of said needles, and clamp plates adapted to cooperate with the grooved sides of said member to confine needles 40 within said grooves.

8. Apparatus for setting in straightened condition a spring-beard knitting needle and arranged to maintain the same in straightened condition during an annealing operation comprising 45 a member having a groove therein complementary to the rear and side surfaces of a finished needle, a groove at right angles to receive the needle butt, said two grooves being in alignment, associated means adapted to engage with and support the outer surface of the needle beard, a bar for aligning the needle beard with said associated means and for spacing the beard relative to the groove of said needle, and a cooperating clamp 50 member adapted to confine a needle within said 55 groove.

9. An apparatus for setting in straightened condition spring beard knitting needles and arranged to maintain the same in straightened condition during an annealing and quenching operation comprising a member having a plurality 60 of grooves therein complementary to the rear and side surfaces of the finished needles, associated means adapted to engage with and support the outer surfaces of the needle beards, a bar for 65 aligning the needle beards with said associated means and for spacing the beards relative to the grooves of said needles, and a cooperating clamp member arranged to confine the needles within the grooves in said member.

10. An apparatus for setting in straightened condition a spring beard knitting needle and arranged to maintain the same in straightened condition during an annealing operation comprising a member having a plurality of grooves therein, 70

each groove being of a form complementary to the shape of the stem of a finished needle, means having grooves therein in alignment with and of less size than said grooves to receive the reduced tips of the needles, and means having grooves therein of the same size as said second mentioned grooves and coplanar with both said two sets of grooves and arranged to receive the portions of the beards of the needles nearer the ends thereof.

11. An apparatus for setting in straightened condition a spring beard knitting needle and arranged to maintain the same in straightened condition during an annealing operation comprising a main portion having a plurality of grooves therein, each of said grooves being of a form complementary to the shape of the stem of a finished needle, means having grooves therein of a reduced size compared to said grooves and in alignment therewith to receive the reduced tips of the needles, means extending back toward said first grooves at an acute angle thereto and having grooves therein of the same size as said second mentioned grooves and coplanar with said first mentioned grooves for receiving the attached portions of the beards of the needles, and a clamp plate for forcing the shank portions of the needles into said first mentioned grooves and having notches in an edge thereof for receiving the free portions of the beards of the needles.

12. Apparatus for setting in straightened condition a spring beard knitting needle and arranged to maintain same in straightened condition during an annealing operation comprising a main portion having a plurality of grooves therein, each of said grooves being formed complementary to the shape of the stem of a finished needle, said portion having also grooves therein in alignment with said first grooves and of reduced size compared thereto for receiving the reduced tips of the needles, and means extending toward said first grooves at an acute angle thereto and having grooves therein of the same size as said second mentioned grooves to receive the attached portions of the beards of the needles, and a bar extending through the beards of a plurality of needles in said grooves to engage the reduced portions thereof with said second and third sets of grooves.

13. An apparatus for setting in straightened condition a spring beard knitting needle and arranged to maintain the same in straightened condition during an annealing operation compris-

ing a body portion having a plurality of grooves therein, each groove being of a form complementary to the shape of the stem of a finished needle, said portion having also grooves therein of reduced size in respect to said first grooves and 5 in alignment therewith for receiving the reduced ends of the needles, means extending back toward said shank receiving grooves at an acute angle thereto and having grooves therein of the same size as said second mentioned grooves, to 10 receive the attached portions of the beards of the needles, a bar extending through the beards of a plurality of needles in said grooves for forcing the reduced sections of the needles into the said second and third sets of grooves, and a clamp 15 plate for forcing the shanks of the needles into said first mentioned grooves and having notches along one of its edges for receiving the free portions of the beards of the needles for holding them in coplanar positions with the remainders of the 20 needles and in close contact with said bar.

14. An apparatus for use in straightening spring beard needles comprising means providing coplanar grooves adapted and arranged to receive the portion of a needle between the apex 25 and the groove, the portion of the beard nearer the apex, and the portion of the beard nearer the tip, and means to press said needle portions into predetermined positions in said grooves and to put pressure on said needle portions while in 30 said grooves throughout an annealing operation to straighten them.

15. The combination with an apparatus as set forth in claim 14 of a bar for extending through the beard portions of a plurality of needles held 35 in the grooves of the apparatus and for supporting the beards against pressure during the annealing operation.

16. An apparatus for use in straightening spring beard needles comprising a plate having 40 a groove therein adapted to receive the rear face of the portion of a spring beard knitting needle between the groove and apex, a plate having a groove therein coplanar with said groove adapted to receive a portion of the beard of said needle 45 nearer the tip, a bar adapted to pass through the beard of the needle in said grooves, and means for clamping a needle beard and the upper end of a needle in said grooves against said bar during an annealing operation to straighten the 50 beard.

GUSTAV GASTRICH.
